WEEDLESS FISHHOOK

Karl E. Larson, Minneapolis, Minn., assignor to
 The Paul Bunyan Bait Company, Minneapolis,
 Minn., a corporation of Minnesota

Application November 17, 1945, Serial No. 629,304

6 Claims. (Cl. 43—42.43)

1

My present invention relates to improvements in weedless fishhooks.

The object of this invention is to provide means on a spoon to releasably hold a fishhook, attached to the spoon, at its point and thereby hold the spoon to function as a closure for the space between the point of the fishhook and its shank, biting action on the spoon and fishhook releasing the fishhook from the holding means.

To the above end, the invention consists of 10 the novel devices and combination of devices hereinafter described and defined in the claims.

In the accompanying drawing, which illustrates the invention, like characters indicate like parts throughout the several views.

Referring to the drawing:

Fig. 1 is a side elevation of my weedless fishhook;

Fig. 2 is a top elevation of the same;

Fig. 3 is a front end elevation of the tongue removed from the spoon, on an enlarged scale; and

Fig. 4 is a side elevation of the tongue shown in Fig. 3, with a portion thereof broken away.

The numeral 6 indicates a spoon having a hole 7 in its inner end portion for a fish-line, not shown, to be attached to the spoon. An apertured lug 8 is secured to the spoon 6, on its convex side, relatively close to the hole 7 at the transverse center of said spoon.

A fishhook 9 is attached to the spoon 6 by having the eye 10 in its shank 11 interlocked with the apertured lug 8. This connection between the spoon 6 and the fishhook 9 permits said fishhook to be placed longitudinally of the spoon 6 with its point 12 turned toward said spoon and at the outer end thereof. The shank 11 is outwardly bowed.

A tongue 13 is hinged to the spoon 6, on its concave side, for swinging movement in a plane that extends longitudinally of said spoon and perpendicular thereto. The hinge for the tongue 13 includes a plate 14 secured to the spoon 6, by rivets 15, at its transverse center. This plate 14 has a pair of upstanding lugs 16 between which the tongue 13 extends and is connected thereto by a pivot pin 17.

The outer end portion 18 of the tongue 13 extends inwardly at right angles to the body of said tongue and has in its outer face a shallow concave seat 19 for the point 12 of the fishhook. When in an operative position, the tongue 13 rests on the outer end portion of the spoon 6, as a stop, and its point 12 extends across the outer end of the spoon 6 close thereto. It is 55

2

important to note that when the tongue 13 is resting on the spoon 6, as a stop, its seat 19 is inwardly of a dead center relative to the pivot pin 17.

To place the point 12 of the fishhook in its seat 19, it is necessary to slightly straighten the shank 11 by springing the same. When the point 12 is in the seat 19, the bowed shank 11 is held under just enough tension to yieldingly hold the point 12 on the seat 19 and prevent relative movement of the spoon 6 and the fishhook 9. This tension, due to the fact that the seat 19 is inwardly of a dead center, also yieldingly holds the tongue 13 against the spoon 6.

15 From the above description, it is evident that when the fishhook 9 is held by its point 12 in the seat 19, the spoon 6 and the tongue 13 act as a closure for the space between the point 12 of the fishhook 9 and the shank 11. It will thus be seen that the fishhook 9 may be thrown among weeds and lily-pads and trolled without catching thereon or on any other obstruction.

When a fish bites the fishhook 9 and the spoon 6, the opposing pressure thereon will swing the tongue 13 away from the spoon 6 and carry its seat 19 and the engaged point 12 outward of dead center and thereby release said point from the seat 19 where the same will become active in the fish's mouth.

20 From what has been said, it will be understood that the weedless fishhook described is capable of certain modifications as to details of construction and arrangement within the scope of the invention described and claimed.

35 What I claim is:

1. A spoon, a fishhook having its shank attached to the spoon with its hook turned toward the spoon, and a member mounted on the spoon for movement toward and from the fishhook and having a seat for the point of the hook from which it is released by opposing inward pressure on the spoon and shank of the fishhook.

2. A spoon, a fishhook having its shank attached to the spoon, and a tongue pivoted to the opposite side of the spoon from the fishhook, the outer end of the tongue affording a seat for the point of the fishhook.

3. The structure defined in claim 2 in which the shank of the fishhook is outwardly bowed from the spoon.

4. A spoon, a fishhook having its shank attached to one side of the spoon, and a tongue hinged to the opposite side of the spoon from the fishhook and resting on the spoon and having a seat for the point of the fishhook that normally

is in a line connecting the point of the fishhook and the hinge of the tongue, and which line is below the point of rest of the tongue on the spoon, the point of said fishhook and the tongue being adapted to move away from the spoon and carry said seat outwardly of said point of rest when opposing, inwardly directed, pressures are applied to the spoon and hook respectively, thereby releasing the fishhook.

5. The structure defined in claim 4 in which movement of the tongue to position the seat below the point of rest of the tongue places the fishhook having its point in the seat under tension.

6. A spoon, a fishhook having its shank attached to one side of the spoon and a tongue hinged to the opposite side of the spoon from the fishhook, the outer portion of the tongue being turned inwardly and extending over the outer end of the spoon and having a seat for the point 20

of the fishhook that normally is in a line connecting the point of the fishhook and the hinge of the tongue, and which line is below the point of rest of the tongue on the spoon, the point of 5 the fishhook and the tongue being adapted to move away from the spoon and carry said seat outwardly of said point of rest when opposing, inwardly directed, pressures are applied to the spoon and hook respectively, thereby releasing the fishhook.
